FOOTBALL PRACTICE DEVICE

Blaine Klum, Oakland, Calif.

Application April 8, 1936, Serial No. 73,355

15 Claims. (Cl. 273—55)

My invention relates to football practice devices, and more particularly to a dummy for use by football players when practicing charging, blocking and tackling.

5 An important object of my invention is the provision of a device of this character which will to a large extent simulate the action of a player and which will require good form on the part of the practicing player to be effectively charged, blocked or tackled.

A further object of this invention is to provide a device of the above-mentioned character the speed of action and mobility of which is substantially as great as that of a live and trained player, whereby it will elude a charger, blocker or tackler who does not employ the proper method of attack.

Another object of this invention is to provide a device of this character which can be used to train football players with results comparable to training against live opponents, without the danger of injuries attendant upon practice of that kind.

Still another object of this invention is the provision of a device of this character which is of simple and inexpensive construction, which is rugged and durable, the breakable parts of which can be readily replaced, and which can be readily set up for use and taken down for storage between periods of use.

Other objects and advantages of the invention will be apparent during the course of the following description.

In the accompanying drawings which form a part of this specification and wherein like characters of reference denote like parts throughout,

Figure 1 is a front elevation of my invention in its operative position ready for use,

Figure 2 is a top plan view thereof showing the range of movement of the dummy in dotted lines.

Figure 3 is an elevation of the device in use, the frame being shown in section,

Figure 4 is a vertical central sectional view through the dummy, parts being shown in elevation,

Figure 5 is a horizontal sectional view on the line 5—5 of Figure 4,

Figure 6 is a detail sectional view on a somewhat larger scale showing the elastic bands and their connections, parts being broken away,

Figure 7 is a detail sectional view taken on the line 7—7 of Figure 6,

Figure 8 is a detail view illustrating the method

of disconnecting the inner portion of the elastic band from the dummy, and,

Figure 9 is a perspective view of the wrench used for removing and replacing the elastic bands.

In the drawings, wherein for the purpose of illustration is shown a preferred embodiment of my invention, the numeral 10 designates a supporting framework which may be of any suitable construction but which is illustrated as comprising a pair of uprights firmly embedded in the ground about 10 or 12 feet apart, connected by a cross bar about 6 feet or more above the ground and a second cross bar spaced about six inches below the surface of the ground.

The central portion of the top cross bar of the frame is provided with a bolt 11 having a hooked lower end projecting below the cross bar, and a similar bolt 12 is secured to the lower embedded cross bar, directly below the bolt 11 and has a hooked portion at its upper end at about the ground level. The hooked bolts 11 and 12 are designed to removably secure my improved practice dummy in a vertical position in the frame.

The dummy is of generally cylindrical shape and is preferably about four feet in length although it may obviously have a somewhat different shape and size. The body of the dummy is formed in three sections of substantially equal length and comprises an outer casing 13 of some suitable flexible material such as canvas or the like. The three sections of the casing 13 are connected by suitable accordion-like pleats 14 which may be formed by turned flaps secured together at a point substantially closer to the axis of the dummy than the outer wall of the casing, as seen in Figure 4. The flaps may be secured together by stitches, staples or other suitable means. The ends of the casing 13 are closed by disks 15 of leather or other suitable material which may be removably secured to the casing by laces 16 or by other means. The leather disks 15 are provided with central openings which receive upper and lower hub members 17 and the disks are rigidly secured to the hub members, 45 which may be of some rigid material such as metal, aluminum or other light metal being preferred. The hub members are provided with central longitudinal bores relieved at their inner portions to receive a flexible tube 18 connecting the hubs 17, and extending longitudinally of the casing 13 and concentric with the axis thereof. The tube may be of any suitable construction and material, such as, for example, a section of fire hose, and is firmly secured to the hubs. 55

The tube 18 is surrounded and closely engaged by a metallic coil spring 19 extending from one hub to the other to prevent collapsing of the tube.

The interior of the dummy between the casing

5 13 and tube 18 is filled with a suitable filling material 20 such as cotton linters or the like, and the hubs and tube provide a central longitudinal bore extending completely through the dummy.

A cylindrical block 21 is arranged midway of 10 the ends of tube 18, and is secured therein by a metal band 22 surrounding the tube and a transverse bolt 23 extending through the band, tube and block. The block 21 may be of wood and may have a metal internally screw threaded sleeve 24 15 extending longitudinally therethrough. If desired the block 21 may be entirely of metal with a screwthreaded bore therein.

The dummy is adapted to be suspended between 20 the hook bolts 11 and 12, and in order to obtain the desired elasticity, I prefer to use elastic or rubber bands 25 to connect the hooks 11 and 12 to the block 21. While it is possible to use springs for this suspension, rubber or elastic is greatly preferred because of the smoother action and 25 greater stretching properties. The bands are of substantial thickness, a diameter of $1\frac{1}{4}$ inches being satisfactory although the size may vary as desired. Each of the bands 25 has its ends vulcanized to form an endless band. One end of 30 each band is forced into a cup 26 of generally oblong cross-section and having a spool or the like 27 removably bolted therein to pass through the band opening, as seen in Figures 4 and 6. Eyelets 28 are integrally formed on the cup 26 to removably engage the hooks 11 and 12.

The inner end of each band is similarly arranged in a cup 29 also of generally oblong shape with a removable spool 30 to retain the band in the cup. The vulcanized portion of the bands are 40 arranged within the cups 26 or 29 to prevent breakage thereof, as indicated in Figures 6, 7 and 8, and the bands are fitted snugly within the cups 26 and 29 as indicated in Figures 5, 6 and 7. Each of the cups 29 is provided with a projecting screw 45 threaded bolt stub 31 adapted to be received within the sleeve 24 of block 21. In order to secure the bolts to the block 21 and remove them therefrom, I make use of a wrench of the form shown in Figures 8 and 9, comprising an elongated handle 32 having arcuate converging wings 33 arranged at one end thereof to form a wedge-like end member which can be inserted in the cups 29 between the two lengths of the band as seen in Figure 8, and rotated to rotate the cups. As the 55 bands are fitted tightly in the cups, the wrench will readily turn the cups and bolts 31.

In practice, the eyelets 28 of cups 26 are passed over hooks 11 and 12 and the dummy is suspended in a vertical position at the center of frame 10. 60 The dummy may be about four feet in length to correspond with the body of a player from shoulder to knees and is preferably arranged with its lower end spaced about a foot or a foot and a half above the ground level as shown in Figure 1. 65 The doubled lengths of elastic 25 extend from the hooks 11 and 12 to the center of the dummy through tube 18, and consequently are long and have an extremely large capacity for stretching.

The dummy is flexible due to its construction 70 and to the provision of the pleated portions 14 and may be bent much in the same manner as a player will bend when blocked or tackled. The tube 18 will bend with the dummy but will not collapse, due to the action of coil spring 19.

75 When charged, blocked or tackled by a player the

dummy will move away from the player and will readily elude him unless he makes a perfect block or tackle. Due to the length and elasticity of bands 25, the dummy is capable of moving through a radius of about four feet in any direction, as indicated in Figure 2, and in this respect resembles an actual player and his normal range of movement. Due to the rapid and smooth action of the dummy, it will elude a player unless the player's technique is good, and will consequently train a player in the proper method of play, as faulty blocking or tackling will not be successful.

In Figure 3 the dummy is shown in use, illustrating its range of movement and the flexibility 15 of the entire dummy. The tube 18 provides a smooth bore in which the bands 25 may work and spring 19 prevents the tube from collapsing and pinching the band. The spring 19, block 21, bolt 23 and cups 29 are arranged within the central 20 portion of the dummy and no rigid parts are arranged on or near the periphery of the dummy to injure a player.

Due to the fast action and mobility of the dummy, which duplicates the actions of a well trained 25 opponent, good form on the part of the player is required. All of the refinements of technique necessary in making a good block or a sustained charge must be used on my invention, which is therefore self-instructing. In tackling, the dummy must be hit squarely and grasped firmly to be held. The important features of construction resulting in the necessary mobility and rapidity of action are believed to be the effective length and elasticity of the bands 25 and the flexibility of 30 the dummy. By reference to Figure 3 it will be seen that the dummy tends to bend at its center after the fashion of a live opponent rather than bending, swinging or pivoting from top or bottom as is the case with practice dummies of the prior 35 art.

The dummy can be taken down for storage by merely unhooking the eyelets 28 from hooks 11 and 12, and the bands can be readily replaced by 40 use of the wrench 32. To remove the bands from cups 29 and 26 it is only necessary to remove the spool retaining bolts, best illustrated in Figure 7. The only parts of the device subject to breakage 45 from wear are the bands 25 which can be replaced at a nominal cost.

The coil spring 19 may be made from circular stock, as shown in the drawings, or it may be flat to more closely engage the flexible tube 18. In practice it is desirable to wrap the coil spring with suitable tape to prevent working of the filling material under the spring coils. For convenience of illustration the tape is not shown on the drawings, so that the construction of the spring and tube will not be obscured.

It is preferred to use the folded elastic band 50 illustrated, but a single band of greater thickness may obviously be employed.

While the invention has been described and 55 illustrated in connection with its application to football, it may obviously be used in any other capacity for which its construction and characteristics adapt it.

While I have shown and described the preferred embodiment of my invention, it is to be understood that various changes in the size, shape and arrangement of parts may be resorted to without departing from the spirit of my invention or the scope of the subjoined claims.

Having thus described my invention, what I claim and desire to protect by Letters Patent is:

1. In a device of the character described, a flexible dummy, a flexible non-collapsible tube extending longitudinally of the dummy, a support, and resilient suspension means connecting the dummy and support and extending into said tube. 5
2. In a device of the character described, a flexible dummy, a flexible non-collapsible tube extending longitudinally of the dummy, a rigid member secured in said tube between the ends thereof, a support, and resilient means connecting the support with the rigid member in the tube. 10
3. In a device of the character described, a pair of spaced supports, a dummy, a tube extending longitudinally through the dummy, a cross-member in said tubes, resilient suspension members connected to said spaced supports, and means to detachably connect the resilient suspension members to the cross-member in the tube. 15
- 20 4. In a device of the character described, a pair of spaced supports, a flexible dummy, a flexible tube extending through said dummy, means surrounding said tube to prevent collapsing thereof while permitting bending of the tube, a cross-member in said tube, and resilient suspension members connecting the cross-member with said spaced supports.
- 30 5. In a device of the character described, a pair of spaced supports, a flexible dummy, a flexible tube extending through said dummy, a resilient coil spring surrounding said tube, a cross-member in the tube, and resilient suspension members connecting the cross-member with said spaced supports. 35
- 35 6. In a device of the character described, a dummy, a flexible tube extending through a portion of the length of said dummy, a coil spring closely engaging said tube to prevent collapsing thereof, a cross-member arranged in said tube, 40 and a resilient suspension member extending into said tube and secured to said cross-member.
- 45 7. In a device of the character described, a pair of spaced supports, a dummy, a tube extending through said dummy, a cross-member in said tube and spaced from the ends thereof, and a pair of endless elastic bands connecting the spaced supports with the tube cross-member. 50
- 50 8. In a device of the character described, a pair of spaced supports, a dummy, a tube extending through said dummy, a cross-member in said tube and spaced from the ends thereof, an endless elastic band connected to each support and extending into said tube from opposite ends thereof, and means to detachably connect said bands to opposite sides of the tube cross-member. 55
- 55 9. In a device of the character described, a support, a dummy, a tube extending into said dummy, an endless elastic band connected to said support and extending into said tube, a terminal member detachably connected to the inner portion of the elastic band, and means to detachably connect said terminal member to the dummy within said tube. 60
- 60 10. In a device of the character described, a pair of spaced supports, a dummy, a tube extending through said dummy, a cross-member in said tube and spaced from the ends thereof, a pair of endless elastic bands, a pair of terminal members removably secured to each band, one of said
- terminal members of each band being connected to a respective one of the supports, said bands extending into opposite ends of the tube, and means to detachably connect the other of said terminal members of each band to the tube cross-member. 5
11. In a device of the character described, a pair of spaced supports, a dummy, a tube extending through said dummy, a cross-member in said tube and spaced from the ends thereof, a pair of endless elastic bands, a pair of terminal members removably secured to each band, one of said terminal members of each band being connected to a respective one of the supports, said bands extending into opposite ends of the tube, means to detachably connect the other of said terminal members of each band to the tube cross-member, and a coil spring closely surrounding the tube to prevent collapsing thereof. 10
12. In a device of the character described, a dummy comprising a flexible casing having a pleated portion on its periphery to facilitate bending of the casing, a flexible tube extending longitudinally through a portion of the length of said casing, a filling material arranged between the tube and the walls of the casing, a support, and a resilient suspension member connected to said support and extending into the tube, said suspension member being connected to the tube at a point spaced from the outer end thereof. 20 25
13. In a device of the character described, a dummy comprising a flexible casing having a pleated portion on its periphery to facilitate bending of the casing, a flexible tube extending longitudinally through a portion of the length of said casing, a filling material arranged between the tube and the walls of the casing, a support, a resilient suspension member connected to said support and extending into the tube, said suspension member being connected to the tube at a point spaced from the outer end thereof, and a coil spring surrounding the tube. 30 35
14. In a device of the character described, a casing having a pleated portion on its periphery to facilitate bending thereof, a pair of hub members secured to the ends of the casing and having longitudinally extending bores therein, a flexible tube connecting the hub members and registering with the bores thereof, a cross-member secured in said tube at a point spaced from the hub members, and resilient suspension members connected to opposite sides of the cross-member and extending through the tube to the exterior of the hub members. 45 50 55
15. In a device of the character described, a casing having a pleated portion on its periphery to facilitate bending thereof, a pair of hub members secured to the ends of the casing and having longitudinally extending bores therein, a flexible tube connecting the hub members and registering with the bores thereof, a cross-member secured in said tube at a point spaced from the hub members, resilient suspension members connected to opposite sides of the cross-member and extending through the tube to the exterior of the hub members, and a coil spring surrounding the tube. 60 65

BLAINE KLUM.
